UNITED STATES PATENT OFFICE.

RICHARD C. POWELL, OF SPRINGFIELD, OHIO.

HANDSAW.

SPECIFICATION forming part of Letters Patent No. 601,480, dated March 29, 1898.

Application filed October 22, 1897. Serial No. 656,015. (No model.)

To all whom it may concern:

Be it known that I, RICHARD C. POWELL, a citizen of the United States, residing at Springfield, in the county of Clark and State of Ohio, have invented certain new and useful Improvements in Handsaws; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in handsaws.

The object of the said invention is to provide a detachable handle for the saw-blade which does not depend entirely upon screws 20 tightening the saw-blade in the slotted portion of the handle in order to hold the blade in position.

The essential features of the invention consist in the peculiar formation of the slots in 25 the connecting end of the saw-blade and in the construction of the main retaining-bolt, as hereinafter more fully described in the specification and pointed out in the claim.

In the accompanying drawings, Figure 1 is 30 a side elevation of a handle and part of a saw-blade embodying my invention. Fig. 2 is a similar side elevation with part of the handle broken away. Fig. 3 is an enlarged elevation of the inner end of the saw-blade 35 detached, showing the retaining-bolts in section. Fig. 4 is an elevation of the main retaining-bolt. Figs. 5 and 6 are views of the screw of the main retaining-bolt.

The handle A may be of any of the numerous forms, with a vertical slot for the reception of the inner end of the saw-blade B. The handle in the present instance has an opening a in its upper portion and an opening a' in its central part for the reception of the retaining-bolts b and b'.

The inner end of the saw-blade has a horizontal slot c' cut in its upper edge, which receives the bolt b', that passes into the slotted part of the handle and secures the upper portion of the blade in position.

c designates a round slot formed in about the vertical center of the inner end of the

saw-blade. In order to avoid any sharp corners that might interfere with the insertion of the saw-blade between the sides of the handle in forming said slot c, the saw-blade is rounded, as at f and f'.

As before stated, the slot c is round or substantially so. The entrance-space e to said slot is, however, essentially narrower than the greatest diameter of the slot, which is for a purpose that will presently appear.

b is the main retaining-bolt, that has a finger-piece d, by which it is turned or screwed onto a screw g, that enters the opening a' on 65 the opposite side of the saw-handle. The said bolt is reduced or has two opposite sides h h flattened to admit of the body of said bolt entering the slot c through the space e. When the saw is moved into the handle, as shown 70 in Fig. 3, the bolt b is in a position to enter said slot, when the saw is inserted, after which the bolt is turned by the fingers to screw it onto the screw g a sufficient distance to tighten it. In thus tightening said bolt it is left in a 75 position with its flattened sides at right angles to the position shown in Fig. 3 and in the position as shown in dotted lines in Fig.

2. When the said bolt is turned to such position, it locks the saw against any removal 80 irrespective of the clamping attachment due to the tightening of the bolt by screwing it onto the screw g. This is an important feature of my invention, as any accidental loosening of said bolt during the operation of the 85 saw will not make the saw-blade liable to become detached, and a tightening of the bolt by the fingers is sufficient to hold the saw in position. The opening on the side of the saw-handle on which the bolt enters is provided 90 with a flanged thimble i, which enters said opening a distance equal to the thickness of the head d' of said bolt. The head g' of the screw g has a pointed projection or lug g'', which enters a corresponding recess i' in the 95 side of the handle shown in dotted lines in Fig. 2 and prevents said screw from turning when the bolt b is being screwed onto it.

In attaching the saw-blade it is first elevated, with the slot c' standing perpendicularly, or nearly so, with the saw-handle about in the position shown in the drawings. In thus elevating the blade the bolt b' enters said slot. The saw-blade is then swung down

on the pivot b' . The bolt b being in a position with the flattened sides h parallel with the sides of the slot c , as shown in Fig. 3, it enters the said slot. The said bolt thus acts as a stop to limit the movement of the saw-blade in the handle.

Having described my invention, I claim—

The combination with a saw-handle, of a saw-blade provided with a horizontal slot in its upper inner edge, and a circular slot below said horizontal slot, the entrance to said circular slot being essentially narrower than its greatest diameter, a bolt penetrating said horizontal slot and the handle, a second bolt

penetrating said circular slot and the handle, the last-named bolt having two opposite sides flattened to enable it to enter the said circular slot and be turned therein to lock the saw to the handle, and a screw entering said last-named bolt to secure it to the handle, all substantially as shown and described.

In testimony whereof I affix my signature in presence of two witnesses.

RICHARD C. POWELL.
